[57] **ABSTRACT**

The blast stove comprises a preferably cylindrical hollow vertical body of refractory bricks closed at the top by a dome of refractory bricks overlying and protruding radially outside the vertical body at the top thereof, the entire body and dome is surrounded by a jacket of steel, and the dome is built up on and is supported by a steel annular element which is in a gas-tight manner connected to the outer steel jacket of the dome and of the vertical cylindrical body, the connection of the said annular element to the steel jacket of the vertical body and/or of the dome extending with respect to the axis of the vertical body alternately in a mainly radial and in mainly axial directions, this annular element being supported by a row of brackets secured to the outer jacket of the vertical body at a larger distance downwards from the upper edge of the vertical body than where the connection of the annular element to the vertical body is positioned, and preferably at at least twice the last mentioned distance. Several species and auxiliary features are also disclosed.

REGENERATIVE AIR HEATER SUCH AS HOT BLAST STOVE

This invention relates to a regenerative air heater, in particular to hot blast stoves for use with blast furnaces, comprising a preferably cylindrical hollow vertical body of refractory bricks closed at the top by a dome of refractory bricks overlying and protruding radially outside said vertical body at the top thereof, the entire structure being surrounded by a jacket of steel of the vertical body and of the dome.

When building air preheaters the development at present is into the direction of ever increasing sizes thereof and the structure should moreover suffice ever increasing requirements of thermal load. This gives rise to structural problems as a result of the occurrence of considerable differences in thermal expansions and contractions of several parts of the structure. Said differences in thermal dilatations etc. cannot be entirely taken up by the normal distribution of stresses in the structure and thus they often give rise to the occurrence of cracks in the refractory lining of the vertical body and of the dome.

A particularly vulnerable area in this respect is the zone where the dome merges into the vertical body. By the choice of a structure as given above and which is known as such, having a dome which protrudes radially outside the vertical body it is possible to solve such difficulties to a considerable extent. This is particularly true for an earlier improvement suggested by the applicant in which the lower edge of the dome is formed by a row of pivoting columns supporting the dome.

However, such structures introduce another structural difficulty. The protruding dome should be supported by a supporting structure positioned around the vertical body, which structure should moreover be part of the gastight outer jacket of the structure. Up to now it has not appeared possible to find a structure for this support which not only gives a good gastight outer jacket, but which also gives a good supporting of the dome without inadmissible stresses occurring in this part of the steel outer jacket. Such stresses are caused by the fact that the upper edge of the vertical body, to which the supporting structure is secured, is hot, whereas the lower edge of the protruding dome is of lower temperature. This lower edge and the part of the supporting structure upon which it rests, will thus expand in a radial direction to a much lesser extent than the upper edge of the vertical cylindrical body. The situation as to the loads in structure caused thereby in this area will not only give rise to the damaging of the steel structure and thus to leakage of the air heater, but also to the occurrence of cracks in the refractory inner lining of the air heater supported by said steel outer jacket.

In view of the above the invention has for its purpose to remove the objections as given above by providing a novel and very simple structure of the air heater. In view thereof the present invention consists in that in an air heater as given in the preamble the dome is built up on and is supported by a steel annular element which is in a gastight manner connected to the outer steel jacket of the dome and of the vertical cylindrical body, the connection of the said annular element to the steel jacket of the vertical body and/or of the dome extending with respect to the axis of the vertical body alternately in a mainly radial and in mainly axial

directions and that this annular element is supported by a row of brackets secured to the outer jacket of the vertical body at a larger distance downwards from the upper edge of the vertical body than where the connection of the annular element to the vertical body is positioned, and preferably at at least twice the last-mentioned distance.

With the aid of this structure it is obtained that the relatively cold lower edge of the dome is supported by 10 brackets connected to the outer jacket of the vertical body in a zone which does not differ very much in temperature from this lower edge and only differs therefrom to an extent, which does not give difficulties and which is deemed admissible. The elements exerting the function of supporting the dome thus are loaded only slightly and to an admissible extent by thermal stresses. The gastight sealing of the dome and the vertical body thus has an elastic nature and shape, so that 20 this is neither loaded inadmissibly by the occurrence of differences in thermal deformation between the upper edge of said body and the support of the dome.

In fact the new structure according to the invention thus gives a situation in which the function of sealing 25 against the outflow of gases and the function of supporting are separated in an efficient manner, so that all elements of the structure functioning for supporting the dome are relatively cold, the elements serving for the sealing against the outflow of gases having elastic 30 deformation properties.

It is therewith not necessary that the annular element, onto which the dome is built up, has almost the same temperature as the brackets and as the part of the outer jacket of the vertical body to which they are connected. This is particularly so because it is quite well imaginable to position the annular element on the brackets in a manner so as to be freely slideable, if desired with a system of sliding blocks between the annular element and the brackets, or longitudinal 40 bearings (linear bearings) or the like.

Structurally such an embodiment is, however, not very attractive as it requires a large number of mutually 45 separate structural elements. Moreover such a solution will entail the requirement that the annular element, the upper surfaces of the brackets and, if present, the sliding blocks or the like, should be assembled in a manner which gives the utmost accuracy as to their mutual positions in order to obtain a uniform supporting of 50 the annular element.

Thus an embodiment according to the invention is preferred in which the annular element is rigidly connected to the brackets.

In order to avoid connecting problems between the 55 outer jacket of the dome and the annular element as a result of the occurrence of thermal stresses, it is possible to couple these two structural parts also by a connecting member having a shape so as to be elastic. However, in practice this has not appeared necessary and 60 even such a structure could entail disadvantages as a result of a too easy possibility of movement between the refractory brick part of the dome and the outer metal jacket thereof.

Thus it is preferred according to the invention to embody such an air heater in such a way that the annular element is immediately, rigidly connected to the outer jacket of the dome, so without intermediary parts, but

is connected to the outer jacket of the vertical body by a connecting part which extends alternately in different directions.

Depending upon the question whether this connecting part has more and longer axially extending parts, the elastic deformability thereof will increase and thus the thermal deformations of the upper edge of the vertical body with respect to the dome will better be taken up. An opposite consideration is, however, that a considerably profiled connecting part takes up more space and thus requires a more pronounced radial protrusion of the dome over the vertical body.

Moreover, such a connecting part entrains a more expensive structure. Thus according to the invention it is preferred to apply an embodiment of the invention in which the connecting part only has three curved parts, in total taking up an angle of 200° to 350°. This boils down to the presence of only a single or a few axially extending parts in the connecting part. It has appeared that this gives the possibility of elastic deformation to an extent which is sufficient in practice. A usual structure detail of the brackets, which could also be applied in the proposed structure, in such that the dome with the lower edge rests upon a plane horizontal part of the brackets. Often the shape of the dome in the proximity of the lower edge is also almost cylindrical. Thanks to this new structure of the air heater it has, however, appeared possible to give the dome a shape which has less curvature, the annular element according to the invention having the shape of a frustoconical body, the lower edge of the dome being perpendicular to this conical surface in the zone where it is supported thereby.

The danger that the dome may slide in the transverse direction with respect to the vertical body is considerably restricted by this feature. In order to avoid also that parts of the dome will slide in a radial direction with respect to other parts thereof it is further preferable to provide the annular element with means for arresting the position of the lower edge of the dome. In particular such means are recommended if the dome along the lower edge consists of pivoting parts according to an earlier proposal by the applicant as indicated above.

A further simplification consists in that the brackets are provided with at least one reinforcing flange at the outside, this flange merging fluently and gradually into the outer lining of the dome. In practice this will be embodied so that these flanges will be part of the steel sheet jacket which forms the outer lining of the dome.

The space between the lower edge of the dome and the upper edge of the vertical body is positioned outside the flow of hot gases through the air heater. This gas quantity present in this zone will give a heat insulating effect between these two elements and thus will also protect the steel connecting part somewhat against too high heating.

However, such protection as a rule is insufficient, in particular in view of the considerable heat radiation below the inside of the dome. In the new air heater the said space is according to the invention preferably filled up at least in part with deformable refractory material. Such material could be a refractory felt or the like.

The invention will now be explained in more detail with reference to the enclosed more or less diagram-

matic drawings, by way of example only. In these drawings:

FIG. 1 shows a hot blast stove according to the invention in side view and partly in vertical section;

FIG. 2 shows detail II in FIG. 1 in vertical section at an enlarged scale;

FIGS. 3, 4 and 5 show the same detail in somewhat different embodiments.

Like parts are indicated by like reference numerals in the several drawings.

In FIG. 1 reference numeral 1 shows an outer jacket of the upper end of the vertical cylindrical body and dome of an air preheater, being the outer steel lining thereof. This air preheater is of the type with an interior stack 21, but a structure according to the invention could as well be applied to air preheaters with an exterior burner stack, such structures being usual and known as such. A wall 22 separates this stack 21 from a space 23, filled with a pile of heat-absorbing refractory bricks not shown. In well-known manner this preheater has an inlet at 24 for combustible gas and combustion air to a burner 25 in the lower end of stack 21, an outlet 26 for heated air and a duct connection 27 for introducing cold air when on blast and for discharging combustion gases when on gas. A grid 28 supports the said pile of bricks. The air preheater moreover has the usual slide valves at the inlets and outlets for gases and air, which are familiar to the expert and thus not shown.

The vertical cylindrical body enclosed by jacket 1 is covered by a dome protruding with its lower edge radially outside said jacket and engaging around the top of the cylindrical masonry within said jacket. The outer steel jacket of said dome is indicated by 2. The lower end of jacket 2 is divided by intermediary recesses into zones or strips 3 which in a manner which will be described below form part of the connection of dome jacket 2 to cylindrical jacket 1.

In contact with the inner wall of the steel jacket 1 of the vertical body a refractory lining is present, indicated diagrammatically by partly shown layers 4, 5 and 6. The refractory dome 7 proper is positioned at some distance interiorly of the outer steel jacket 2 of the dome and extends downwardly past the upper edge of layers 4, 5 and 6 to a greater radial distance from the axis of the heater. At a distance from and outside dome 7 a refractory heat insulating layer 8 of bricks is present in contact with the outer steel jacket 2.

Each strip 3 constitutes part of an I-shaped beam having a web 9 and an opposite flange 10, and said beam is, at a considerable distance below the upper edge of layers 4, 5 and 6, welded to the steel outer jacket 1 of the vertical body. In this zone the temperature of the jacket is substantially lower than at the upper edge of the vertical body. If the steel outer jacket 1 in this zone is not sufficiently rigid, it is possible to apply a suitable reinforcement in this zone, such as a continuous surrounding steel annulus between the steel jacket 1 and the I-shaped beams. It is also possible to provide the web 9 at its lower end with flanges extending transversely over the outside of the steel jacket and in contact therewith over a large area. Such an annulus or such flanges would have a vertical section in FIG. 2 as shown in a dotted line and as indicated by 29.

Between the zone of the largest protrusion and radial extension of the dome jacket 2 and the upper end of the jacket 1 there is a connecting part 11 being stepped in shape. Thanks to this stepped shape it is possible for this connecting part to connect jacket parts 1 and 2 in a gastight manner. On the central step of this stairs the refractory dome 7 rests.

The upper end 12 of the brackets is also shaped in a stepwise manner. Between this upper edge 12 and part 11 there are sliding blocks 13, 14 and 15, which may be secured or not to one of the faces in contact therewith, so to the upper surface 12 of the brackets 9 or to the lower surface of part 11. This makes it possible to take up any deformation of part 11 in a radial sense with respect to the brackets because the contacting parts are easily allowed to slide with respect to each other.

FIG. 3 gives a simplified structure of the same detail as FIG. 2. In FIG. 3 the connecting wall 11 of the outer metal jacket as shown in FIG. 2 is replaced by a conical element 16, onto which the dome 7 rests, and an elastic connecting part 17. The conical element 16 is rigidly secured to the upper side of the brackets. In this embodiment a movement in a radial sense of the dome 7 with respect to the upper surface of the brackets is excluded. To this end the inner flange 10 of the brackets is continued to extend upwardly a short distance past conical element 16, so that the lower edge of the dome 7 rests in a deepened recess, which it cannot easily leave. The supporting forces between dome 7 and element 16 are restricted to a force perpendicular to the surface of element 16 thanks to the conical shape of this element and to the fact that dome 7 in this part extends exactly perpendicularly to element 16.

In FIG. 4 an alternative of the structure of FIG. 3 is shown in which the connecting part 18 of the metal jacket smoothly merges into both the upwardly extended part of the inner flange 10 and into the metal jacket 1. Thereby a higher elastic deformability is obtained.

FIG. 5 shows yet another alternative. This differs from the alternative of FIG. 4 in that the metal jacket connecting part 19 is not positioned as an upward extension of the inner flange 10, but as an inward extension of the conical element 16. This simplifies the structure as to the method of making it. The arresting of the lower edge of dome 7 against movement in a radial sense is in this structure obtained by applying, e.g. by welding, two longitudinal circular ribs 20 all around on element 16. The lower bricks of dome 7 have recesses, so that they fit over these ribs.

We claim:

1. A regenerative air heater such as a hot blast stove for a blast furnace plant, comprising a preferably cylindrical hollow vertical body of refractory bricks closed at the top by a dome of refractory bricks overlying and protruding radially outside said vertical body at the top thereof, the entire structure being surrounded by a jacket of steel of the vertical body and of the dome, characterized in that the dome is built up on and is supported by a steel annular element which is in a gas-tight manner connected to the outer steel jacket of the dome and of the vertical cylindrical body, the connection of the said annular element to the steel jacket of the vertical body and/or of the dome extending with respect to the axis of the vertical body alternately in a mainly radial and in mainly axial directions and that this annular element is supported by a row of brackets secured to the outer jacket of the vertical body at a larger distance downwards from the upper edge of the vertical body than where the connection of the annular element to the vertical body is positioned, and preferably at at least twice the lastmentioned distance.
2. An air heater according to claim 1, characterized in that the annular element is rigidly secured to the brackets.
3. An air heater according to claim 1, characterized in that the annular element is immediately rigidly connected to the outer jacket of the dome, so without intermediary parts, but is connected to the outer jacket of the vertical body by a connecting part which extends alternately in different directions.
4. An air heater according to claim 3, characterized in that the connecting part includes three curved parts which in total occupy an angle of 200° to 350°.
5. An air heater according to claim 1, characterized in that the annular element has the shape of a frustoconical body and that the lower edge of the dome is positioned perpendicularly to this element.
6. An air heater according to claim 1, characterized in that the annular element is provided with means for arresting the position of the lower edge of the inner refractory brick dome against radial movement.
7. An air heater according to claim 1, characterized in that an outer flange of the brackets smoothly merges into the outer metal jacket of the dome.
8. An air heater according to claim 1, characterized in that the space between the dome, the vertical body and the connecting part between annular element and outer jacket of the vertical body is at least in part filled with deformable refractory material.
